UNITED STATES PATENT OFFICE

JAMES R. GRIFFETH, OF NORWALK, CONNECTICUT, ASSIGNOR OF ONE-HALF
TO MOSES H. GLOVER, OF SAME PLACE.

HAT-BRIM TRIMMER.

SPECIFICATION forming part of Letters Patent No. 663,965, dated December 18, 1900.

Application filed March 8, 1900. Serial No. 7,828. (No model.)

To all whom it may concern:

Be it known that I, JAMES R. GRIFFETH, a citizen of the United States, residing at Norwalk, county of Fairfield, State of Connecticut, have invented a new and useful Machine for Trimming Curled Hat-Brim, of which the following is a specification.

My invention has for its object to provide a simple, durable, inexpensive, and easily-adjusted and easily-operated machine for trimming the brims of curled hats, this operation being sometimes known in the art as "planing" and sometimes as "paring" the brims.

With the above end in view I have devised the novel brim-trimming machine, of which the following description, in connection with the accompanying drawings, is a specification, reference characters being used to designate the several parts.

Figure 1 is a side elevation of the machine complete; Fig. 1^a, a detail sectional view corresponding therewith; Fig. 2, a plan view; Fig. 3, a similar view showing the position of the oscillating cutter-plate relatively to the body of the rotating head when the cutter is acting upon one of the quarters of a hat-brim, the brim-plate being partly broken away and the standard in horizontal section; Fig. 4, an enlarged sectional view on the line 4-4 in Fig.

2; Fig. 5, an enlarged plan view of the inner end of the carrying-slide, showing the yoke and rollers; Fig. 6, an elevation looking in the direction of the arrow in Fig. 3, one of 35 the brim-plates being in section on the line 6-6 in Fig. 1; Fig. 7, an enlarged plan view of the inner end of the cross-plate, the standard being in section; and Fig. 8 is an enlarged sectional view on the line 8-8 in Fig. 1.

40 A denotes a suitable base or bed plate which may be made of metal or wood and is adapted to be secured in place upon a bench or table in any suitable manner, as by screws passing through holes 20.

45 B denotes a standard extending upward from the bed, and C a cam-track resting upon legs 21, which are rigidly secured to the base. The operative surface of this cam-track is a curved plane lowest at the ends, highest at 50 the sides, and inclined at the quarters to cor-

respond substantially to the plane of an ordinary hat-brim.

The hat-body to be operated upon is held in place by an internal expander D, which may be of any ordinary or preferred construction 55 and is shown as operated by an oscillatory rod 22 in the standard, provided at its lower end with a hand-lever 23, adapted to engage a rack 24. Just below the expander and rigidly secured to the standard is a brim-plate 60 E, which is convex from end to end—that is to say, the brim-plate is lowest at the ends, highest at the sides, and inclined at the quarters in order to correspond substantially with the ordinary curvature of a hat-brim. 65

25 denotes side plates which support the upward curves at the sides of the brim. These side plates are made adjustable to provide for different sizes of hats in any simple and convenient manner. In the present instance I have shown the side plates as carrying eyes 26, whose shanks 27 extend through slots 28 in the brim-plate and engage, respectively, the right and left threads of a screw F, which is carried by lugs 29, extending from the brim-plate. This screw is free to turn in the lugs, but is held against lateral movement therein, and a finger-piece 30 is provided at one end for convenience in operating it. 70 75 80

G denotes a cam-plate detachably secured to a cam-plate holder H in any suitable manner, as by thumb-screws 31. This cam-plate may of course be made in one or more pieces, as preferred. In the present instance I have 85 shown the cam-plate as made in two pieces, the ends of which are in contact when in place, so as to make the edge, which is the operative portion, continuous. This edge is lowest at the ends, highest at the sides, and inclined at 90 the quarters, the curvature from end to end corresponding substantially with the curvature of the brim-plate and the cam-track—i.e., the curvature of an ordinary hat-brim. The configuration of the edge of the cam-plate as 95 seen in plan determines the line of movement of the cutter in making the trimming cut, as will be more fully explained. The cam-plate holder is rigidly secured to the standard in any suitable manner. In the 100

present instance I have shown the standard as provided with an angular portion 32, which engages a corresponding opening in the cam-plate holder, the latter resting on a shoulder 5 on the standard and being held in place by a nut 33.

34 denotes the cutter, which is carried by a vertically-swinging arm 35, which also carries an adjustable guard 36, and is pivoted to a cutter-slide 37. The guard is shown as adjustably secured to the cutter-slide by means of a thumb-screw 38, which passes through a slot 39 in the shank of the guide. The cutter-slide is adapted to be adjusted in or out in 15 ways 40 in an oscillating cutter-plate 41. The cutter-slide is shown as locked in position in the cutter-plate after adjustment by means of a set-screw 42. The oscillating cutter-plate is rigidly secured to an oscillating rod 20 43, said oscillating rod being free to turn in and being carried by a slide 44, which I have termed the "carrying-slide." This slide is adapted to reciprocate in the body 45 of a rotating head K. This rotating head is shown 25 as provided with a socket 46 and the carrying-slide with a shoulder 47. A spring 48, bearing against the bottom of the socket and against the shoulder, acts to move the carrying-slide and the parts carried thereby for 30 ward and retain them in operative position, as will be more fully explained.

49 denotes a yoke carrying grooved rollers 50, which are adapted to engage the edge of the cam-plate. This yoke is rigidly secured 35 to the oscillating rod, which, as already stated, is pivoted at the inner end of the carrying-slide. The oscillating cutter-plate, which is also rigidly secured to the oscillating rod, is in the present instance superposed on a plate 40 51, which is really a part of the carrying-slide, although in the present instance the only connection between plate 51 and the carrying-slide is the oscillating rod. Plate 51 in the present construction slides in ways 45 52 in the body. At the rear end of the oscillating cutter-plate is an arc-shaped slot 53. The rear end of the oscillating cutter-plate is retained in place by means of a pin 54, which passes through the slot and firmly engages 50 plate 51.

The body 45 of rotating head K is provided with a handle 55 for convenience in operation and is rigidly secured to a cross-plate 56. Upon the under side of the cross-plate 55 are lugs 57, to which yokes 58 are pivoted. These yokes carry rollers 59, which are adapted to travel on cam-track C, as clearly shown in Figs. 1 and 6.

It will be obvious that when grooved rollers 60 50, journaled in the yoke on the carrying-slide, travel up the inclines of the cam-plate (corresponding to the quarters of a hat-brim) said yoke will be tilted—that is to say, the rollers will lie in a plane at a more or less 65 acute angle to the horizontal plane, one roller being slightly higher than the other. It will be noted in Fig. 5 that carrying-slide

44 is made angular. The socket 46, in which it slides, is of course made to correspond therewith in cross-section. This is in order 70 to cause the entire rotating head to be tilted to correspond with the position of yoke 49, as is clearly shown on Fig. 6, in connection with which see Fig. 3. In order to permit this tilting of the rotating head, cross-plate 75 56 is provided with a transversely-elongated opening 60, which receives freely a sleeve 61, which is adapted to slide on the standard. This sleeve is provided with oppositely-extending pins or lugs 62, which lie in longitudinal sockets 63 in the upper side of the cross-plate. 80

64 denotes a spring bearing against the under side of the cam-plate holder and against the sleeve and acting by means of pins 62 85 upon the cross-plate, so that the rollers 59 in yoke 58 are kept closely in engagement with the cam-track, the spring yielding and permitting the cross-plate, and with it the entire rotating head and the parts carried thereby, 90 to rise when rollers 59 travel up the inclines of the cam-track and causing it to move downward again when said rollers travel down the inclines, pins or lugs 62 at the same time permitting the rotating head to tilt freely when 95 yoke 49 on the carrying-slide is tilted by the engagement of rollers 50 with the inclined quarters of the cam-plate.

The operation is briefly as follows: The parts of the machine are all permanent—that 100 is to say, they do not require to be shifted in changing from one style of hat to another, with the exception of the cam-plate. In changing from one size of hat to another the operator moves slide-plates 25 in or out, as 105 may be required, by means of screw F. Changes of style will ordinarily not require new side plates. Usually, therefore, in changing from one style of hat to another the only change of parts required in the machine is 110 the removal of the cam-plate and the substitution of a new one. This is a very important feature of my invention, as it enables me to make changes in style at a merely nominal expense, it being of course apparent that 115 cam-plates of varying configuration and in one or more pieces can be produced at a relatively trifling expense. In use the operator places the hat-body to be operated upon over the expander and secures it there by oscillation of the hand-lever. The swinging arm is then lowered to place, the guard placed under the edge of the brim, and the cutter passed through the brim, after which the rotating head is swung once around, the entire 120 operation of placing a hat on the machine and trimming the brim being performed in less time than it takes to describe it. The starting position is at one of the ends of the brim. In this position the oscillating cutter-plate carrying the cutter-slide and cutter lies 125 parallel with the carrying-slide, as is clearly shown in Fig. 2. At the first quarter, however, as clearly shown in Fig. 3, the oscillat-

130

ing cutter-plate, owing to the position in which yoke 49 will be placed by the special portion of the edge of the cam-plate which is at that instant engaged by rollers 50, will be 5 swung forward of the carrying-slide. At the side of the oscillating cutter-plate and the carrying-slide will again be parallel, as at the starting-point. At the second quarter the body and carrying-slide will pass ahead of 10 the oscillating cutter-plate. At the end said parts will be parallel again. At the third quarter said parts will be in the same position as at the first quarter, which is clearly illustrated in Fig. 3, and at the fourth quarter 15 said parts will again be in the same position as at the second quarter, this position of the parts not being illustrated in the drawings, owing to the fact that the principle of operation is made clear in Fig. 3, the relative position of the oscillating cutter-plate and the carrying-slide and other parts of the rotating head being merely a transposition of that illustrated in Fig. 3.

The machine as a whole is simple, durable, 20 and practically impossible to get out of repair, an important feature being the relatively inexpensive mode in which the machine is adapted to different styles of hats.

It will of course be understood that my invention is by no means limited to the special details of construction illustrated in the drawings, but that the details of construction 25 may be greatly varied without departing from the principle thereof.

Having thus described my invention, I 30 claim—

1. The combination with a standard and means for holding a hat-body to be operated upon, of a cam-plate and a cam-track, said 35 cam-plate and cam-track being lowest at the ends and highest at the sides for the purpose set forth, and a rotating head having pivoted yokes and rollers which travel on the cam-track and a carrying-slide having a pivoted 40 yoke and rollers engaging the edge of the cam-plate.

2. The combination with a standard, a brim-plate lowest at the ends and highest at the sides for supporting a hat-body to be operated upon and means for retaining a hat-body 45 thereon, of side plates for supporting the curves at the sides of the brim, the cam-plate and cam-track, substantially as described, and a rotating head having pivoted yokes and 50 rollers which travel on the cam-track and a carrying-slide having a pivoted yoke and rollers engaging the cam-plate.

3. The combination with a standard, a brim-plate having slots 28 and means for retaining 55 a hat-body on said brim-plate, of side plates for supporting the curves at the sides of a brim and having eyes 26 whose shanks engage the slots, a right and left threaded screw carried by the brim-plate and engaging the 60 eyes whereby the side plates may be adjusted toward or from each other, the cam-plate and cam-track and a rotating head having piv-

oted yokes and rollers engaging the cam-track and a carrying-slide having a pivoted yoke and rollers engaging the cam-plate. 70

4. In a machine of the character described the combination with a cam-track and a cam-plate lowest at the ends and highest at the sides, substantially as described, of a rotating head having pivoted yokes and rollers engaging the cam-track and a carrying-slide having a pivoted yoke and rollers engaging the cam-plate. 75

5. In a machine of the character described the combination with a cam-plate and a cam-track lowest at the ends and highest at the sides, of a rotating head comprising a cross-plate having pivoted yokes carrying rollers which engage the cam-track, a body carried by said cross-plate and a spring-actuated carrying-slide in said body having a pivoted 80 yoke and rollers engaging the cam-plate.

6. In a machine of the character described the combination with a cam-plate lowest at the ends, highest at the sides and inclined at the quarters, of a rotating head having an angular recess, a correspondingly-shaped spring-actuated carrying-slide in said recess and a yoke pivoted to said slide and carrying rollers which engage the cam-plate whereby when 95 the head is rotated the inclines of the cam-plate will tilt the carrying-slide and with it the rotating head.

7. In a machine of the character described the combination with a cam-track lowest at the ends, highest at the sides and inclined at the quarters, of a rotating head including a cross-plate carrying pivoted yokes having rollers which engage the cam-track on opposite sides 100 so that when the head is rotated the inclines 105 of the cam-track will cause the head to rise and fall.

8. In a machine of the character described the combination with a cam-plate and a cam-track lowest at the ends, highest at the sides 110 and inclined at the quarters, of a rotating head comprising a cross-plate having pivoted yokes and rollers which engage the cam-track, a body carried by said cross-plate and having an angular recess, a correspondingly-shaped 115 carrying-slide in said recess, a yoke pivoted to said slide and carrying rollers which engage the cam-track and a spring acting to move the slide forward, so that when the head is rotated the inclines of the cam-track will 120 cause the head to rise and fall and the inclines of the cam-plate will tilt the carrying-slide and with it the rotating head and parts carried thereby.

9. In a machine of the character described 125 the combination with a standard, a cam-track and a cam-plate lowest at the ends, highest at the sides and inclined at the quarters, of a rotating head comprising a cross-plate having a transversely-elongated opening and longitudinal sockets 63, a spring-actuated sleeve 130 on the standard which lies in said opening and is provided with pins engaging the socket, a body carried by said cross-plate and a car-

rying-slide in said body having a pivoted yoke and rollers engaging the cam-plate.

10. In a machine of the character described the combination with a standard and a cam-track lowest at the ends, highest at the sides and inclined at the quarters, of a rotating head having a cross-plate with an opening and sockets 63, yokes pivoted to said cross-plate and carrying rollers which engage the cam-track, a sleeve on the standard lying in said opening and having pins engaging the sockets and a spring acting to press the sleeve and with it the cross-plate downward.

11. In a machine of the character described the combination with a standard, a cam-track and a cam-plate both lowest at the ends, highest at the sides and inclined at the quarters, of a rotating head comprising a cross-plate with a laterally-elongated opening 60 and sockets 63, yokes pivoted to said cross-plate and carrying rollers engaging the cam-track, a spring-actuated sleeve on the standard lying in said opening and having pins engaging the sockets, a body carried by the cross-plate, a spring-actuated angular slide in said body and a yoke pivoted to said slide and carrying rollers engaging the cam-plate.

12. In a machine of the character described the combination with a cam-plate lowest at the ends, highest at the sides and inclined at the quarters, of a rotating and vertically-movable head, an angular spring-actuated slide in said head and a yoke pivoted to said slide and carrying rollers engaging the cam-plate, the inclines of said cam-plate causing the head to tilt in one direction or the other in addition to its rotary and vertical movements.

13. The combination with a cam-plate holder and a removable cam-plate lowest at the ends, highest at the sides and inclined at the quarters, of a rotating vertically-movable and tiltable head K and a slide carried by said head and itself carrying a pivoted yoke and rollers which engage the cam-plate.

14. In a machine of the character described the combination with cam-plate G, rotating head K, and means for imparting vertical reciprocatory movement to said head as it is rotated, of a spring-actuated carrying-slide, a yoke pivoted to said slide and carrying rollers engaging the cam-plate, an oscillating rod carried by the yoke and a plate 41 rigidly secured to the oscillating rod.

15. In a machine of the character described the combination with cam-plate G, rotating head K, and means for imparting vertical reciprocatory movement to said head as it is rotated, of a spring-actuated carrying-slide, a yoke pivoted to said slide and carrying

rollers engaging the cam-plate, a rod 43 carried by the yoke and oscillating therewith, and an oscillating cutter-plate carried by said rod.

16. In a machine of the character described the combination with the cam-plate G, of rotating head K, carrying-slide 44, yoke 49 pivoted to said slide and carrying rollers engaging the cam-plate, a spring acting to move said slide forward, rod 43 fixed to said yoke and oscillating therewith and an oscillating plate 41 carried by said rod.

17. In a machine of the character described the combination with cam-plate G, of rotating head K having ways 52, a spring-actuated carrying-slide, a yoke pivoted to said slide and carrying rollers engaging the cam-plate, a plate 51 adapted to slide in the ways, an oscillating rod carried by the yoke and passing through plate 51, a plate 41 carried by the oscillating rod and having a curved slot and a pin passing through said slot and engaging plate 51.

18. In a machine of the character described the combination with means for holding a hat-body in place, a cam-plate G, a rotating vertically-movable and tiltable head K, a slide 44 carried by said head and a yoke pivoted to said slide and engaging the cam-plate, of an oscillating cutter-plate carried by the yoke, a cutter-slide adjustably secured to the oscillating cutter-plate, a vertically-swinging arm pivoted to the cutter-slide and a cutter and guard carried by said arm.

19. In a machine of the character described the combination with means for holding the hat-body in place, a cam-plate G, a rotating vertically-movable and tiltable head K and a spring-actuated slide in said head carrying a swinging yoke and rollers which engage the cam-plate, of an oscillating cutter-plate carried by the yoke and a cutter and guard adjustably secured to the oscillating cutter-plate.

20. In a machine of the character described the combination with a cutter, a guard therefor and means for holding a hat-body in place, of a cam-plate G, a rotating vertically-movable and tiltable head K, slide 44, pivoted yoke 49 carrying rollers which engage the cam-plate and an oscillating cutter-plate carried by the yoke and itself carrying the cutter and guard.

In testimony whereof I affix my signature in presence of two witnesses.

JAMES R. GRIFFETH.
